CLAIM

The ornamental design for a slice drum, as shown and described.

DESCRIPTION

FIG. 1 is a top perspective view of a first embodiment of a slice drum showing our new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a right side elevation view thereof;

FIG. 8 is a left side elevation view thereof;

FIG. 9 is a top perspective view of a second embodiment of a slice drum showing our new design;

FIG. 10 is a bottom perspective view thereof;

FIG. 11 is a top plan view thereof;

FIG. 12 is a bottom plan view thereof;

FIG. 13 is a front elevation view thereof;

FIG. 14 is a back elevation view thereof;

FIG. 15 is a right side elevation view thereof;

FIG. 16 is a left side elevation view thereof;

FIG. 17 is a top perspective view of a third embodiment of a slice drum showing our new design;

FIG. 18 is a bottom perspective view thereof;

FIG. 19 is a top plan view thereof;

FIG. 20 is a bottom plan view thereof;

FIG. 21 is a front elevation view thereof;

FIG. 22 is a back elevation view thereof;

FIG. 23 is a right side elevation view thereof; and,

FIG. 24 is a left side elevation view thereof.

The broken line in the figure drawings represents unclaimed environment only and forms no part of the claimed design.
